GAS BURNER

Application filed March 21, 1929. Serial No. 348,903.

This invention relates to gas burners for use in connection with the fire boxes of furnaces, stoves and ranges.

A primary object of the invention is to so construct a burner of this character that it may be easily installed in heaters the doors of which are too small to admit the passage of the burner as a whole.

Another object of the invention is to provide a burner of this character so constructed that a dual colored flame of high efficiency will be produced and the flame outlet area of which is so graduated that back flash is prevented.

Another object of the invention is to so construct a burner of this character that it may be of any desired configuration and which is equipped with adjustable burner units interchangeable for use in connection with any shape of burner.

Another object of the invention is to provide a burner having a plurality of burner units, each of which is equipped with flame ports so constructed that the dropping of rust, dirt and other foreign matter into the expansion chamber is prevented.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a perspective view of a circular burner embodying this invention with two of the burner units removed.

Fig. 2 is a similar view showing a straight burner constructed in accordance with the invention with the valve assembly removed;

Fig. 3 is a longitudinal section partly in elevation showing the valve assembly which is used in connection with the straight burner;

Fig. 4 is a perspective view partly in section of the body of a straight burner with one of the mixing tubes shown attached;

Fig. 5 is a perspective view showing a detail of a mixing tube with a fragment of a burner unit attached;

Fig. 6 is a perspective view with parts

broken out and in section of one of the burner units with its top shown open and arranged in juxtaposition ready for assembly; and

Fig. 7 is a vertical longitudinal section through one of the burner units and the mixing tube with the body structure of the burner shown in transverse section.

In Fig. 1 an annular burner 1 is shown made in the form of a hollow metal casing 2 substantially inverted U-shaped in cross section and provided around the periphery thereof with a plurality of openings 3 in the outer wall thereof which merge at their upper ends into circumferentially extending slots 4 which are designed to receive mixing tubes 10 whereby the burner units are connected with the body of the burner. Any desired number of these units may be employed according to the size of the burner to be constructed and as shown in Fig. 1 six of

such units are illustrated and the openings provided for two others which have been removed, and which are connected by the mixing tubes 10 with the burner body or shell 2 and numbered 15, all of them being constructed exactly alike hence one only will be described in detail.

Located within the shell 2 of the burner body 1 is a gas pipe 5 designed to be connected by a branch 6 with a gas main and which is equipped with a plurality of jet openings 7 in its outer wall one of which is arranged opposite each of the mixing tube receiving openings 3 and is shown clearly in Fig. 1. Around the gas pipe 5 in the casing 2 is an air chamber 8 which is supplied through the open bottom of the casing 2.

Each mixing tube 10 comprises a body 11 shaped to conform to a chamber 16 in the burner unit and which is designed to be entered through an opening 17 in said unit as is shown clearly in Fig. 6. The outer end of the tube 10 has an upstanding T-shaped head 12 designed to fit in a slot 4 of the burner body whereby said tube is securely connected with said body, the bore 13 of the tube being arranged opposite the gas jet 7 in the pipe 5 so that the combined air and gas will be fed through the tube 10 to the burner units.

Each burner unit 15 is shown substantially

in the form of a rectangular hollow box with a horizontal partition 18 extending longitudinally thereof from the top of the opening 17 and terminating short at its rear end of 5 the end wall of said casing. This partition forms between it and the bottom of the burner unit body a compartment 16 to receive the mixing tube 10. It is thus seen that these tubes 10 are adjustable relatively to the burner unit so that the burner units may be disposed closer to or further away from the body of the burner 1 as may be desired. Each burner unit 15 is provided with a removable top 19 around the edges of which 15 are formed downwardly inclined notches 20 which form when the top is in closed position flame ports through which the fuel from the interior of the burner unit escapes and at which point it is lit to form the flame. These 20 flame ports 20 being arranged in the vertical sides and ends of the burner units and inclined as shown prevent the falling of rust, dirt and other foreign matter into the expansion chamber.

25 Depending from the inner or lower face of the top 19 is a fin 21 here shown made substantially triangular in form with an aperture 22 extending through its apex to receive a pin 23 which is also extended transversely 30 through apertures 24 formed in the opposed side walls of the burner unit and by means of which the top 19 is securely connected with the body of the unit.

It will be obvious that the head 12 of the 35 mixing tube or pipe 10 is shaped to conform to the opening 3 in the side wall of the burner casing 2 so that when the parts are assembled a loose fit will be insured to provide for ready removal of the tube when desired. As here 40 shown this opening is substantially U-shaped in form and the head 12 is correspondingly shaped as shown in Fig. 5 to fit therein. When the mixing tube is in position it receives the jet of fuel directly in the center 45 of the open end of the tube, thus avoiding all danger of leakage around outside of tube.

In the form shown in Fig. 2 the burner instead of being round is substantially oblong or rectangular in general contour the shell 50 or casing 2a thereof being in the form of an elongated rectangular box open at its bottom to provide for the entrance of air to the chamber 8a and in which is mounted the gas supply pipe 5a here shown fixedly connected 55 with the side walls of the casing 2a by means of integral lugs or fins 25. This rectangular casing 2a as shown clearly in Fig. 4 is provided at its opposite sides with openings 3a corresponding to those 3 shown in the other 60 form of the invention and which are designed to receive heads 12 to the mixing pipes 10 carried by the burner units, it being obvious that these mixing heads and pipes are the same in both forms of the invention and may be used 65 for connecting the burner units which are

also the same with any shape burner casing, provided such casing be equipped with the openings to correspond to the shape of the head 12 of the tube 10.

The burner shown in Fig. 2 is constructed 70 along the same general lines as that shown in Fig. 1 except that the configuration of the casing is different, the burner units and the mixing tubes being the same.

The gas supply pipe 5a shown in Figs. 2, 75 3, and 4 in connection with the straight or rectangular burner casing is internally threaded at one end as shown at 26 to receive the valve bushing 27 which is located at one end of the gas supply pipe while at the other 80 end thereof is the valve seat fitting 28 the seat 29 of which is designed to receive the needle valve 30 operable by means of a hand wheel 31 carried by the outer end of the valve stem 32 and which controls the amount of gas admitted to the pipe 5a from the gas main, the connecting pipe of which is shown at 40.

The valve assembly which controls the admission of gas to the burner casing or rather to the pipe 5a in said casing through 90 which pipe it is discharged to the mixing tube 10 through the apertures 7a, is also designed for use in connection with the supply pipe 6 of the circular burner 1, it being understood that the shape of this assembly is made 95 to conform to such uses.

From the above description it will be seen that the mixing tubes 10 are all detachable from the burner units and from the burner casing and that they are adjustable relatively 100 to the burner units to adapt the burner to fit fire boxes of different sizes. Moreover the connection of the burner unit by the mixing tube with the burner casing provides for the units being interchangeable for use in connection with either straight, circular, or other shaped burner casings.

It is also to be understood that any desired 110 number of units may be employed in connection with the burner, eight being here shown in both forms of the invention illustrated.

It is also to be understood that the means of supplying air to these burners is by the simple expedient of admitting air to the base or ash pit of a heater in connection with 115 which the burner is used, the use of an ordinary stack damper being the only means of regulation needed in this connection.

In the installing of a burner constructed in accordance with this invention obviously 120 it may be disassembled and the casing first mounted in the fire box and then the mixing tubes and the burner unit assembled by inserting them through the doors of the furnace or other heater which while admitting the passage of the individual units would be too small for the burner if the parts were made integral. Moreover this separation of the parts provides for the repair and renewal of 125 the individual elements when necessary and 130

in which all parts are instantly accessible for cleaning or service.

The burner units 15 each has within it an expansion chamber 33 into which the air and gas mixture is entrained through the mixing tube and finally issues out of the flame ports 20 of the top of the burner unit where it is ignited and produces a dual colored flame of highest efficiency and owing to the graduated 10 outlet area of the flame ports back flash is prevented.

A burner constructed as herein shown and described has practically no carbon formed therein, is efficient in the generation of heat, 15 economical in the consumption of fuel, being simple and durable in construction, and is inexpensive to manufacture.

Without further description it is thought that the features and advantages of the invention will be readily apparent to those skilled in the art, and it will, of course, be understood that changes in the form, proportion and minor details of construction may be resorted to, without departing from 25 the spirit of the invention or its scope as claimed.

I claim:

1. A burner of the class described comprising a burner body, in the form of a hollow 30 casing open to the atmosphere, a gas supply pipe mounted in said casing having outlet apertures arranged at intervals, said casing having openings positioned opposite said aperture, mixing tubes having T-shaped 35 heads to be detachably mounted in said casing openings, and having bores arranged opposite the discharge apertures of the gas pipe, and a burner unit connected with each mixing tube.

40 2. A burner of the class described comprising a burner body in the form of a hollow casing open to the atmosphere, a gas supply pipe mounted in said casing having outlet apertures arranged at intervals, said casing 45 having openings positioned opposite said apertures, the upper walls of said openings having lateral slot-like extensions, mixing tubes having upstanding T-shaped heads to be mounted in said casing openings and interlocking engage said lateral extension, said tubes having bores arranged opposite the 50 discharge apertures of the gas pipe.

3. A burner of the class described comprising a burner body in the form of a hollow 55 casing open to the atmosphere, a gas supply pipe mounted in said casing having outlet apertures arranged at intervals, said casing having openings positioned opposite said apertures, the upper walls of said openings 60 having lateral slotlike extensions, mixing tubes having upstanding T-shaped heads to be mounted in said casing openings and interlocking engage with said slot extensions, said tubes having bores arranged opposite 65 the discharge apertures of the gas pipe and

a burner unit adjustably mounted on each of said mixing tubes and into which the tubes discharge.

4. A burner of the class described comprising a hollow annular body with spaced openings in the outer wall thereof, said body being open to the atmosphere, a gas supply pipe mounted in said body and having outlet apertures arranged opposite the openings in the body, mixing tubes to be mounted in said body openings, said tubes and body having elements for interlocking engagement to detachably connect the tubes to the body, the bores of the tubes being arranged opposite the discharge apertures of the pipe, and a 70 75 burner unit carried by each of said mixing tubes.
